UNITED STATES PATENT OFFICE.

WILLIAM P. DEVINE, OF BOSTON, MASSACHUSETTS, ASSIGNOR TO CONSOLIDATED FASTENER COMPANY, OF PORTLAND, MAINE.

FASTENER.

SPECIFICATION forming part of Letters Patent No. 672,095, dated April 16, 1901.

Application filed October 10, 1900. Serial No. 32,647. (No model.)

To all whom it may concern:

Be it known that I, WILLIAM PATRICK DEVINE, a citizen of the United States, residing at Boston, in the county of Suffolk and Commonwealth of Massachusetts, have invented 5 a new and useful Improvement in Fasteners, of which the following is a full specification.

My invention relates to snap-fasteners consisting of a ball member and a socket member, either or both of these members being resilient, so that they can be sprung or snapped together and retain their engagement under normal condition.

My invention consists in an improved eyelet-piece for attaching the ball member and the socket member to the material on which the fastener is set. As commonly used, an attaching-eyelet consists of a flange and a central barrel, the barrel being drawn from the center of the flange. In my improved eyelet I form the barrel from radial arms extending outwardly from the circumference of the flange. These arms or fingers are folded back onto the flange and then extended outwardly 25 at right angles to form the barrel. For convenience of manufacture the same eyelet-piece may be used for attaching both the ball member and the socket member, as herein-after shown and described.

Referring to the accompanying drawings, Figure 1 shows the blank from which my eyelet-piece is formed. Fig. 2 shows the completed eyelet-piece. Fig. 3 shows the socket member of my fastener as commercially sold, the 35 material and eyelet-piece being shown as in relative juxtaposition thereto. Fig. 4 shows the socket member attached to any material. Fig. 5 shows the two parts of the ball member before being assembled. Fig. 6 shows the ball member as commercially sold with the attaching eyelet-piece attached and inserted in the material before riveting. Fig. 7 shows the ball member attached to any material. Fig. 8 shows the blank from which the "bird- 45 cage spring" of the ball member is formed.

As shown in the drawings, my improved eyelet-piece A, formed from the blank shown in Fig. 1, consists of the flange 1 and radial arms 2. These arms 2 are folded backward and 50 down upon themselves and then struck upward, as shown in Fig. 3. Before being given

its final shape, as shown in Fig. 3, the eyelet-piece is drawn into the cup or cylindrical shape shown in Fig. 5 and the flange 1 and arms 2 are so proportioned that the outer edge 3 of 55 the flange forms part of the cylindrical wall to the piece, as shown in Fig. 5. When the eyelet-piece is given its final form, as shown in Figs. 2 and 3, this outer edge 3 of the flange is folded back on itself, forming a flange of 60 double thickness, as shown.

The flange 1 has a central perforation 4, having an inwardly-turned edge 5. This inwardly-turned flange serves a particular purpose in both the ball member and the 65 socket member, as will be hereinafter described.

The socket member of my improved fastener consists of the eyelet-piece A and the cap B. The cap B as commonly used consists of the shell 6 and anvil-piece 7. The eyelet-piece A is inserted through the material and meets the anvil-piece 7 of the cap B. By suitable means these two pieces are pressed together, with the effect that the arms 75 2 of the eyelet-piece are deflected outwardly against the anvil-piece 7 and clenched beneath the inwardly-turned edges 8 of the cap B, as shown in Fig. 4. The inwardly-turned edge 5 of the eyelet-piece A thus forms an 80 orifice to the chamber within the cap B, into which the stud may be snapped. This upturned edge 5 assists materially in clasping the neck of the stud firmly and prevents undesirable looseness in the union of the stud 85 and socket.

For the stud member of my improved fastener I preferably use a bird-cage spring formed up from the blank C, Fig. 8, having the fingers 10. This bird-cage is formed into 90 the shape shown in Fig. 5, having the dome 11, with the ends of the fingers 10 projecting horizontally at its base. In this form the bird-cage is inserted in the eyelet 5 during its intermediate step, as shown in the same 95 figure. When the eyelet-piece is completed, the finger ends 10 are inclosed between the parts of the flanges 1 and 3, as shown in Fig. 6. To prevent the finger ends from pulling out of engagement with the flange of the eyelet-piece, I provide the fingers at the base of the dome 11 with the depressions 12, which 100

are engaged by the inwardly-turned edge 5 of the eyelet-piece, and thus prevent the finger ends from being withdrawn after the flange 3 is closed upon them.

5 My stud member is attached to the material by means of the eyelet-piece A, the prongs of which are thrust through and turned back upon the material by means of a suitable die, as shown in Fig. 7.

10 I claim—

1. In a fastener, an attaching-piece having a central opening surrounded by an inwardly-turned flange, and integral radial arms extended from the disk, the disk being turned back and in a direction to form a doubled portion and the arms bent vertically at substantially right angles to the base, substantially as described.

2. In a fastener, a socket member, comprising a cap-piece having an anvil, and an attaching-piece consisting of a disk having a central opening surrounded by an inwardly-turned flange, the metal of the disk being turned back and down upon itself and the upper fold thereof formed with arms adapted to engage between the outer face of the anvil and the inturned flange of the cap.

3. In a fastener, a ball member, comprising a bent cage-stud having annular depressions at the base of the fingers and extended horizontal flanges, and an attaching-piece formed with a central opening surrounded by an inwardly-turned flange to engage in the depressions of the stud, and the metal of the attaching-piece being bent to form a doubled

portion with an intervening space to receive and hold the base-flanges of the stud, and formed with arms bent at right angles to the base, whereby the stud may be connected with and held to the material, substantially as described.

4. In a fastener, an attaching-piece, consisting of a base-flange composed of metal bent back and down upon itself and having a central opening surrounded by an inwardly-turned flange, and integral vertically-directed attaching-arms, substantially as and for the purpose specified.

5. In a fastener consisting of a ball member and a socket member, the ball member consisting of the spring-piece C, in combination with an eyelet-piece having a double flange and circumferential barrel forming arms, substantially as shown and described.

6. In a fastener consisting of a ball member and a socket member, the ball member consisting of the spring-piece C having depressions 12 in combination with the attaching eyelet-piece A having an inwardly-turned flange 5, substantially as shown and described.

In testimony whereof I have signed my name to this specification, in the presence of two subscribing witnesses, on this 7th day of September, A. D. 1900.

WILLIAM P. DEVINE.
